UNITED STATES PATENT OFFICE.

LUTHER W. HARWOOD, OF TROY, NEW YORK, ASSIGNOR TO FULLER,
WARREN & CO., OF SAME PLACE.

DESIGN FOR A PARLOR-STOVE.

Specification forming part of Design No. 6,322, dated December 24, 1872.

To all whom it may concern:

Be it known that I, LUTHER W. HARWOOD, of the city of Troy, in the county of Rensselaer and State of New York, have invented and produced a new and original Design for Parlor-Stoves, of which the following is a specification, reference being had to the accompanying wood-cut or engraving of a stove which embodies my said design.

One part of my said design consists of the oblong curved panels A, having the net-work ornamentation b thereon, and the ornamented border-molding c, all shaped and arranged together so as to appear substantially as represented in the aforesaid wood-cut. Another part consists of the particular combination of ornamental forms constituting the upper border D of the fire-pot section of the stove, substantially as shown in the aforesaid engraving. Another part consists of the combination of the ornamented panels A and border D on the fire-pot section of a stove so as to appear sub-

stantially as represented in the accompanying cut. Another part consists of the design for the frames E for the mica-lights, as distinguished by the rounded tops and straight or somewhat curved bottoms and sides, and ornamented moldings f thereon, all so as to present substantially the same appearance as is represented in the aforesaid engraving.

What I claim as my invention is—

1. The design for the panels A and border-molding c, as herein described.
2. The design for the border D, as herein set forth.
3. The combination of the border D and ornamental panels A, as set forth.
4. The design for the mica-light frames E, as herein described.

LUTHER W. HARWOOD.
